UNITED STATES PATENT OFFICE

168,323

ROSARY CASE OR THE LIKE

Frank J. Van Wyk, Chicago, Ill.

Application July 19, 1951, Serial No. 15,941

Term of patent 14 years

(Cl. D58—2)

To all whom it may concern:

Be it known that I, Frank J. Van Wyk, a citizen of the United States and a resident of Chicago, in the county of Cook, State of Illinois, have invented a new, original, and ornamental Design for a Rosary Case or the like, of which the following is a specification, reference being had to the accompanying drawing, forming a part thereof.

Fig. 1 is a top plan view of a rosary case or the like, showing my new design;

Fig. 2 is a front edge elevational view thereof; and

Fig. 3 is a rear edge elevational view thereof. The back of the case is plain.

I claim:

The ornamental design for a rosary case or the like, as shown and described.

FRANK J. VAN WYK.
